APPARATUS FOR PRODUCING GAS

James L. Hamilton, Box 3728, Charlotte, N.C., and Frank Joseph Nolan, 312 Filmore St., Hollywood, Fla.; said Nolan assignor of seventeen percent to Wilson H. Hamilton, St. Augustine, Fla.

Filed Mar. 16, 1961, Ser. No. 96,196

8 Claims. (Cl. 55—234)

This invention relates to an improved apparatus for producing a highly combustible, efficient gas from liquid hydrocarbons, such as rubber solvents, hexane and various other types of solvents, for use as fuel for jet type gas burners such as are used for heating and refrigerating buildings and appliances contained therein.

Due to the fact that many buildings do not have access to a piped public-utility source of natural or manufactured gas and due to the inconvenience in having so-called bottled gas (propane) delivered to such buildings, notwithstanding the expense of such gas to the consumer, various prior attempts have been made to develop an economical system for producing combustible gas from relatively inexpensive hydrocarbon liquids, which system could be embodied in an inexpensive, self-contained and portable apparatus capable of furnishing a supply of efficient gas of optimum specific gravity or fuel-to-air mixture at any time regardless of ambient temperature conditions.

Although such prior systems have met with some degree of success, they have been unsatisfactory for use with jet type gas burners and, to our knowledge, their inefficiency has been such that they have never been used commercially or, at least, their use has been discontinued. To our knowledge, prior art gas producing equipment has utilized a substantially closed container containing a liquid absorbing medium in the form of pulverized charcoal, steel wool, or textile fibers, partially or entirely immersed in or spaced above a supply of hydrocarbon liquid, which liquid was at or very near ambient temperature or may have been heated, and wherein compressed air was caused to flow at relatively high pressure and velocity through or past the liquid and/or the absorbing medium.

The dominant draw-back of such prior art apparatuses has been their general inefficiency, particularly at the time they were first put into use following several hours of dormancy and for an interval up to or more than an hour after they were put into use, because during such interval, the gas escaping from the jets of a gas burner connected to the prior art gas producing apparatus would be of excessively high specific gravity so the amount of liquid hydrocarbon suspended in the air exceeded that which would burn efficiently and an undesirable, low-heat, yellow flame would thus emanate from each of the jets of the burner.

As is known, a yellow flame indicates that only a fractional part of the hydrocarbon molecules in the gas are being consumed by the flame. Thus, the remainder of the hydrocarbon molecules would escape into the air and form carbon monoxide and create a hazardous problem which might have resulted in asphyxiation of the occupants of the room and which, at best, would produce an undesirable carbonaceous coating on cooking utensils placed over such flame. Further, the burner would require constant attention during such intervals, since it was necessary to reduce the flow of gas at the jets from time to time to avoid overheating the contents of the utensils as the quality of the gas would gradually improve.

The main reason why the gas produced by such prior devices was necessarily of low quality during an initial interval of utilization of such devices, following a sub-

2

stantial period of dormancy, was because of the fact that, in order for such devices to produce an efficient gas following such initial intervals of utilization, it was necessary to manufacture such devices so as to produce gas of the desired specific gravity while in continuous use for a longer period of time. However, there were no provisions made in such prior devices for filtering out or removing from the air any excess liquid fuel (above that which must be suspended in the air to produce efficient combustion) which necessarily became suspended in the moving air when such prior devices were initially utilized following a substantial period of dormancy. This so-called excess liquid fuel became suspended in the moving air at such times of initial utilization because the capillary action of the liquid absorbing medium would cause the said medium to become overladen with liquid fuel during such periods of dormancy so the air moving past or through such medium would continue to pick up and suspend therein excess amounts of hydrocarbon molecules for some considerable period of time until the rate of flow of the air, the pressure of the air, the "recovery rate" of the absorbing medium, and the volatility of the liquid all became proportionally compatible or arrived at equilibrium such as to cause just the right amount of hydrocarbon molecules to become suspended in the air as it moved past the liquid and the absorbing medium to produce efficient gas at the jets of the burner and such as to produce a blue flame.

The term "recovery rate" as used herein denotes the rate at which an absorbing medium, partially immersed in or immediately adjacent to a supply of liquid hydrocarbon, will absorb an amount of hydrocarbon liquid sufficient to replace only that amount which can be removed therefrom by moving air currents therethrough at a given pressure and temperature; i.e., the rate at which the absorbing medium absorbs the liquid by capillary action and the rate at which the moving air absorbs the liquid from the absorbing medium are in equilibrium.

It is therefore an object of this invention to provide a novel apparatus for producing an efficient gas from liquid hydrocarbons having a boiling point above ambient atmospheric temperature which overcomes the defects in the prior art devices discussed above and wherein air, at very low pressure and at moderate temperature, is introduced into an enclosure and moved past an absorbing means, preferably in the form of suspended bleached cotton rovings, partially immersed in such liquid, the liquid also being maintained at a moderate temperature. The air then flows past a dry loose, bleached cotton absorbing means, preferably in the form of dry suspended, low-twist bleached cotton rovings which absorb any liquid from any of the air which may have suspended therein an amount of liquid exceeding the necessary optimum amount to provide a gas having a specific gravity within prescribed limits, such that the gas is highly combustible and efficient.

It is another object of this invention to provide an improved apparatus for producing gas from liquid hydrocarbons of the character described, in which air within an enclosure is maintained at a very low pressure above atmospheric pressure and impinges against a wet absorbing means, preferably in the form of suspended, bleached cotton rovings whose lower ends are immersed in liquid hydrocarbon.

Although the wet absorbing members may become overladen with hydrocarbon liquid while the apparatus is dormant, when the apparatus is initially utilized, the low pressure air then flows past and through dry absorbing members consisting of suspended, lightly twisted or crimped bleached cotton strands, slivers or rovings whose lower ends are spaced above the hydrocarbon liquid. The dry cotton rovings are of such texture and density that any hydrocarbon molecules whose suspension in the air

cause the gas to exceed an optimum specific gravity are absorbed by the dry cotton rovings and the gas then passes from the enclosure to the jets of the gas burners. Thus, the specific gravity of the gas is held within such limits that all the gas is efficiently consumed by the flame at the gas jets even during the initial interval of utilization of the apparatus.

For some reason which is not apparent to us, when the dry bleached cotton rovings are in proper proportion to the wet or partially immersed absorbing means, which proportion must finally be determined empirically, the dry bleached cotton rovings only remove from the air any droplets or molecules of hydrocarbon which are in excess of the amount of such droplets or molecules of hydrocarbon which must remain suspended in the air in order to produce a clear, hot, blue flame at the jets of the gas burners. This condition continues even though the extent to which the air may have become overladen with hydrocarbon gradually diminishes for an indeterminate interval following the instant at which the apparatus is utilized after having remained dormant for some time. This is also the case after said indeterminate interval has passed. In other words, when the moving air at said low pressure flows past and through the wet absorbing means and picks up sufficient hydrocarbon molecules only to cause the gas to be of the desired optimum specific gravity, the dry bleached cotton rovings through and past which the gas subsequently flows in its course to the gas burner or burners absorb very little if any of the hydrocarbon then suspended in the air.

This application is a continuation-in-part of our co-pending application Serial Number 706,079, filed December 30, 1957, now abandoned, and entitled "Method and Apparatus for Producing Gas."

Some of the objects of the invention having been stated, other objects will appear as the description proceeds, when taken in connection with the accompanying drawings, in which—

FIGURE 1 is a side elevation of a preferred embodiment of the improved apparatus of the present invention;

FIGURE 2 is a view looking at the left-hand side of FIGURE 1;

FIGURE 3 is a view looking at the right-hand side of FIGURE 1;

FIGURE 4 is an enlarged transverse sectional view through an improved blower for effecting constant pressure within the housing of the apparatus, showing the impeller in position for producing a relatively low pressure in the housing of the apparatus;

FIGURE 5 is a view similar to FIGURE 4 showing the impeller in position for producing relatively high pressure and showing a novel valve construction in association therewith;

FIGURE 6 is an axial sectional view through the blower taken substantially along line 6—6 in FIGURE 4;

FIGURE 7 is an enlarged transverse vertical sectional view through the apparatus taken substantially along line 7—7 in FIGURE 1;

FIGURE 8 is a schematic isometric view of the improved apparatus omitting the wicking and a side and top wall thereof for the purpose of indicating the circuitous path followed by air currents passing through the apparatus;

FIGURE 9 is a longitudinal vertical sectional view through the apparatus, with parts broken away, taken substantially along line 9—9 in FIGURE 2; and

FIGURE 10 is an inverted sectional plan view through the apparatus taken substantially along line 10—10 in FIGURE 9, but being on a reduced scale.

As heretofore stated, various apparatuses for producing gas from liquid hydrocarbons have been provided heretofore, but have not been entirely satisfactory due to the fact that, after the prior art apparatus had been shut down or inoperative for an extended period of time, such as all night, the igniting of a burner the following morn-

ing would result in a long yellow flame, which was indicative of an excess of hydrocarbon molecules relative to the volume of air as compared to that which could be efficiently consumed by the flame; i.e., the specific gravity of the gas would be too high. This inadequate flame would generally continue for an indeterminate period of time; i.e., from five minutes to an hour, during which the specific gravity of the gas would gradually reduce and an efficient combustible gas would then be directed to the burner so that a satisfactory flame would be produced. Under such conditions, the apparatus had to be adjusted at varying intervals so as to provide a constant gas quality. The present apparatus overcomes the above and other defects and such apparatus will now be described in detail.

The Enclosure

Referring more specifically to the drawings, the numeral 20 broadly designates an enclosure or tank, preferably in the form of a substantially rectangular sheet metal housing or tank. Tank 20 may be square or in the form of an elongate tube closed at opposite ends or of other form without departing from the spirit of the invention. In its preferred embodiment, tank 20 includes suitably interconnected vertical walls 21—24 and top and bottom walls 25, 26. For purposes of orientation, walls 21 and 22 shall be termed hereinafter as front and rear walls, respectively, and side walls 23 and 24 will be termed as left-hand and right-hand side walls, respectively.

Spaced closely above bottom wall 26 is an irregular or corrugated false bottom 30 which is preferably made from sheet metal and which forms the bottom of an air diffusion chamber 34 and which also supports a supply of liquid hydrocarbon, the preferred level of which is indicated at L. The false bottom 30 and main bottom 26 of enclosure 20 define an air heating chamber 31 therebetween, the rear wall 22 being provided with a filtered or screened opening 32 for ingress of air, from the surrounding atmosphere, into the heating chamber 31. The heating chamber has a longitudinal partition 27 therein engaging the lower edges of the V-shaped portions of the false bottom 30, for supporting the same and causing diagonal flow of air currents through chamber 31.

It will be noted that the upper and lower surfaces of false bottom 30 are of substantially corresponding configuration to provide transversely extending ridges and valleys in alternation throughout the length of enclosure 20. It will be observed in FIGURES 9 and 10 that a sinuous or serpentine heating element 33 is suitably secured to the lower surface of false bottom 30 and is so shaped as to form a plurality of substantially parallel runs which extend transversely of enclosure 20 and which runs are preferably disposed immediately beneath the transverse ridges formed on irregular false bottom 30.

Suitable conductors in a cable or electrical conduit 36 extend outwardly from one end of heating element 33 through rear wall 22 and are connected to a suitable thermostatic switch 37, which switch is preferably of the manually adjustable type, and from the other side of which conductors 40 extend to a suitable source of current, not shown. The thermostatic switch 37 may be of the well-known household type or of any other desired construction and, therefore, a detailed description thereof is deemed unnecessary. A suitable heat-conducting element or bulb 38 is connected to the thermostatic switch and submerged in the liquid L whereby the thermostatic switch 37 controls the temperature of the liquid and, consequently, the air in heating chamber 31.

It is thus seen that air flowing from the atmosphere through the heating chamber 31 may be heated, and the liquid L may also be heated, by heating element 33. The end, side and bottom walls defining chamber 31 are preferably provided with an insulation covering 41 so as to minimize loss of heat from heating chamber 31.

Diffusion chamber 34 is divided into a plurality or series of compartments *a-h* by means of a substantially centrally located longitudinally extending partition 45 and longitudinally spaced transverse partitions 46-51. The partitions 45-51 extend from the top wall 25 downwardly to the level of the upper edges of the ridges of false bottom 30 whereby the valleys in the upper surface of false bottom 30 permit the liquid L to flow into the lower portion of all such compartments. It will be noted that transverse partitions 46-51 are spaced above the valleys formed in the false bottom 30 so as to permit the liquid hydrocarbon to pass between the false bottom 30 and the lower edges of the transverse partitions.

Referring to FIGURE 8, it will be observed that partitions 45-51 are provided with respective passageways or openings 55-61. Opening 55 is disposed at the rearmost portion of the longitudinally extending partition 45, openings 56, 58, 59, 61 are disposed at the outermost portions of respective transverse partitions 46, 48, 49, 51, and openings 57, 60 are disposed at the proximal or innermost portions of the center transverse partitions 47, 50. This provides a series of passageways in the partitions which are disposed in horizontally staggered relationship to effect a somewhat serpentine flow to the air passing through diffusion chamber 34. The openings 56, 57, 58, 55, 59, 60, 61 are also of progressively reduced area in that order. The compartments *a-h* are interconnected by the relatively small openings 56-58, 55 and 59-61 so as to obstruct or retard the flow of low pressure air through the compartments and thereby produce uniform pressure substantially throughout each compartment. This arrangement of partitions in enclosure 20 is very important to the successful operation of this apparatus, because of the extremely low pressure which must be used in order to produce gas according to our method, and wherein it is necessary that the air is dispersed throughout the absorbing members to be presently described.

The Absorbing Means

All the compartments *a-g* of diffusion chamber 34 have primary or wet suspended absorbing members 65 therein, secondary or dry absorbing members 65a being provided in the final stage compartment *h*. The absorbing members 65, 65a may be suspended from adjacent the top wall 25 by any suitable means. In this instance, the upper portions of the side walls 23, 24 and opposite sides of the upper portion of the longitudinally extending partition 45 have angle bars 66 thereon on which spaced rods 67 are supported and over which members 65 are looped. All the absorbing members, with the exception of those in the final stage compartment *h*, have their lower ends immersed in the liquid hydrocarbon so the partially immersed absorbing members 65 raise the liquid over the supporting rods or members 67 by capillary attraction.

The absorbing members 65a in the final stage compartment *h* are relatively short as compared to the absorbing members 65 so their lower ends terminate in spaced relation above the level L of the liquid hydrocarbon. The absorbing members should be highly absorbent and should be capable of high capillary action. Loosely twisted, bleached cotton strands, slivers or rovings have been found to be the only material which may be used in compartment *h* for absorbing from the gas any molecules of hydrocarbon which are in excess of those molecules which must remain suspended in the gas in order that the gas will burn with an efficient blue flame. Also, it is highly desirable that absorbing members 65 are in the form of loosely twisted, bleach cotton strands, in order to minimize the size of the mass of such members 65 for producing a given volume of gas.

Although some diffusion of the air and hydrocarbon molecules occurs throughout diffusion chamber 34, it occurs to the greatest extent in compartments *a-g*. Accordingly, the compartments *a-g* may be termed "dif-

fusion compartments" and compartment *h* may be termed as a "conditioning compartment."

As heretofore stated, in order to produce gas from liquid hydrocarbons, such as commercial hexane, and wherein the specific gravity of the gas is maintained within predetermined limits such as to result in efficient complete combustion and thus produce a clear blue flame, we have found that the air delivered into the apparatus and emanating from the jets of the burner or burners must be under very low pressure. Experiments have shown that the pressure in the enclosure 20 must be maintained constant at from 1½ to 5 inches water gauge pressure; i.e., .0542 to .1805 pound per square inch or approximately ¾ to 3 ounces per square inch gauge pressure. Such low pressures are usually measured in inches of water by use of a manometer.

Thus, the material which absorbs liquid hydrocarbon and from which liquid hydrocarbon is to be absorbed by the air moving thereby and/or therethrough must be sufficiently loose, open or porous to permit air to circulate therethrough without being obstructed thereby to any substantial extent and the absorbing medium must be of high capillarity, since the higher the capillarity of the material, the higher is the recovery rate of the material. This is extremely important in the final stage compartment *h* since the nature of the absorbing medium must be such as to permit a given amount of the hydrocarbon molecules to remain suspended in the air passing therethrough and thereby while any hydrocarbon molecules exceeding said given amount must be absorbed by the absorbing medium located within the final stage compartment *h*.

We have conducted experiments with many different types of absorbent materials in order to develop a material which would produce the desired result. Such materials included synthetic filaments and fibers, such as nylon, rayon filaments and fibers; balsa wood, roved wool fibers, woven cotton lamp wicking, puverized charcoal, fuller's earth, lightly compressed or packed balls of bleached cotton, unbleached strands of cotton roving, bleached strands of low-twist cotton roving, etc. As a result of these experiments, only loose bleached cotton, preferably in the form of strands, such as rovings and slivers, was found to have all the characteristics necessary in order to produce the desired result in the final stage or conditioning compartment *h*. Other absorbent materials may be used in the diffusion compartments *a-g*, however, as will be later explained.

It was found that woven cotton lamp wicking, synthetic filaments and fibers, rayon filaments and fibers, balsa wood, compressed balls of bleached cotton, strands of wool roving, unbleached strands of cotton roving, pulverized charcoal and fuller's earth were all of insufficient absorbency to remove hydrocarbon molecules from the low pressure gas when it was of too rich a mixture such as to reduce the gas to the relatively low specific gravity necessary for efficient combustibility.

In order to minimize the size of the gas producing apparatus and thereby facilitate economical construction thereof, it is preferable that bleached cotton fibers, in the form of loosely twisted rovings, also be used in the diffusion compartments *a-g*. Experiments have shown that woven cotton lamp wicking, synthetic filaments and fibers, rayon filaments and fibers, balsa wood, compressed balls of bleached cotton, and wool rovings could be used as the primary or wet absorbing means 65 only by increasing the size of enclosure 20 to such extent that it would be too large and expensive to manufacture for practical use.

Assuming, for example, that diffusion chambers *a-g* are of such size as to accommodate the correct amount or mass of partially immersed, loosely twisted, bleached cotton strands, such as to produce an efficient gas when subjected to the slow moving low pressure air when a gas cock or gas cocks are open for a considerable pe-

riod of time, when an equal mass of any one of the other types of absorbing means last described is substituted for the loosely twisted cotton strands or rovings, each of the other types of absorbing means then has insufficient capillarity to maintain the low pressure air moving through the diffusion compartments at sufficiently high specific gravity in order to produce an efficient blue flame. Similar unsatisfactory results were obtained when pulverized charcoal and fuller's earth were each substituted for the loose bleached cotton strands in diffusion compartments *a-g*.

It was found that, by moving air at relatively high pressure through pulverized charcoal or fuller's earth, the air would pick up sufficient hydrocarbon to form a gas of the desired specific gravity. However, in the latter instance, the gas jets would have to be too large for practical use and the gas would escape from the jets at such velocity that the flame would be projected a substantial distance from the jets, notwithstanding the fact that the gas would then become admixed with the surrounding atmosphere to such extent that the flame would still be a relatively long, low-heat yellow flame, thus defeating the purpose of the present invention. Further, the loose bleached cotton strands *65a* in compartment *h* were then of little value, since due to the necessary high pressure and velocity of the air as it passed through the pulverized charcoal or fuller's earth, the dry loose bleached cotton strands could not absorb any noticeable amount of hydrocarbon molecules from the gas even if the gas contained more of such molecules than it should in order to burn efficiently.

During these experiments, it was also found that balsa wood was too fragile and would disintegrate when used as the wet absorbing means and compressed balls of bleached cotton were of insufficient porosity and would not permit the air to circulate therethrough. Although strands of wool roving and unbleached cotton roving had a higher capillarity than the other absorbent materials with which we experimented, with the exception of the bleached cotton strands, the capillarity thereof and the consequent recovery rate thereof were still insufficient for use in the same size relatively small diffusion compartments *a-g* as could be used to accommodate the required amount of bleached cotton strands to produce the desired result. It was found that bleached cotton rovings had approximately ten times the capillarity and recovery rate of unbleached cotton rovings.

The absorbent material which produced the most satisfactory results in both the diffusion compartments *a-g* and the conditioning compartment *h* of the prototype apparatus was in the form of lightly twisted strands of from .10 to .20 hank bleached cotton roving or sliver, the strands of which had $\frac{3}{4}$ to $1\frac{1}{2}$ turns per inch twist imparted thereto during the roving operation. With the low pressure air, it is preferred that approximately eight inches of such rovings are exposed above the liquid *L* in the diffusion compartments *a-g* and that approximately one inch of the latter rovings are immersed in the liquid supply in order that the wet rovings have the correct recovery rate. As heretofore stated, various types of absorbent materials of relatively high capillarity may be used in compartments *a-g*, but only dry, loose cotton strands, such as loosely twisted bleached cotton rovings or slivers, may be used in conditioning compartment *h*.

The wet absorbing means *65* in the drawings is shown in the form of strands of bleached cotton rovings, as is preferred. The amount of wet rovings *65* in proportion to the amount of dry rovings *65a* is not necessarily as illustrated in the drawings, however, since the ratio of the exposed portions of the wet rovings *65* to the dry rovings *65a* may actually be between 35 to 1 and 45 to 1, depending upon the size of the enclosure *20*, the air pressure therewithin, the temperature, and the volatility of the liquid hydrocarbon.

The final stage or conditioning compartment *h* of diffu-

5 sion chamber *34* preferably has a foraminated shelf *68* therein disposed between the level of the liquid *L* and the lower ends of the dry absorbing members *65a* to further insure that the dry absorbing members *65a* do not come in direct contact with the hydrocarbon in the liquid state and will therefore remain substantially dry. Shelf *68* is shown in the form of a plate or screen, preferably made from sheet metal and provided with suitable openings therein. Plate *68* is suitably secured to the proximal surfaces of side wall *24*, longitudinally extending partition *45*, front wall *21* and front transverse partition *51*.

10 The liquid hydrocarbon may be maintained at the desired level *L* by any suitable means, such as a liquid level float controlled member *72* which may be supported on rear wall *22*. The liquid hydrocarbon enters float controlled member *72* through a pipe *73* from a suitable supply tank, not shown, and passes through member *72* and into the lower portion of diffusion chamber *34* through a pipe *75*. Liquid level controllers are well-known and a detailed description of member *72* is deemed unnecessary.

The Blower

15 As heretofore stated, the pressure at which the gas is maintained in the enclosure *20* is highly critical and is so relatively low that an ordinary blower or pump will not serve the desired function. Also, the pressure producing means should be so constructed so as to be minutely adjustable in order to accommodate variations in the manufacture of the enclosure *20* and the elements contained therein, since different enclosures may vary as to the capacity thereof, the liquid level *L* may vary in different enclosures and the bleached cotton rovings *65* and *65a* may vary as to mass and displacement.

20 To this end, we have provided a centrifugal blower broadly designated at *80*, the housing of which comprises a substantially flat end wall member *81* and an axially opposed conical wall member *82* which is connected to the wall member *81* by a flanged annular portion *83* (FIGURES 4, 5 and 6). The housing of blower *80* contains an impeller *85* mounted on a reduced outer end of a motor shaft *87* extending from an electric motor *90*. Motor *90* is mounted on a motor support *91* to which the relatively flat wall member *81* of blower *80* is also suitably secured. Motor support *91* is suitably secured to the top wall *25* of enclosure *20*.

25 The conical wall *82* of blower *80* has an air intake opening *93* in its central portion to which a conduit *94* is connected. It will be observed in FIGURES 1, 2, 9 and 10 that conduit *94* extends downwardly from blower *80* and is connected to the front wall *21* of enclosure *20* for communication with the heating chamber *31*, preferably in diagonally opposed relation to the air ingress opening *32*. Impeller *85* comprises a relatively large disk or wheel *96* mounted on the reduced end of motor shaft *87*. A flanged hub *97* is also mounted on the reduced end of shaft *87*.

30 Hub *97* and disk *96* are secured in the desired adjusted relationship on the reduced portion of motor shaft *87* by any suitable means, such as a nut *100* (FIGURES 4, 5 and 6). The impeller *85* of blower *80* also includes a plurality of circularly spaced blades or vanes *101*, preferably made from a relatively thin flexible material such as stainless steel. Opposite ends of each vane *101* are pivotally connected, as at *102*, and *103*, to the disk *96* and hub *97*, respectively. It will be noted that the vanes *101* are of greater length than the normal distance between the pivot points *102*, *103* when considered radially of the axis of the impeller *85* (FIGURE 4).

35 It will be noted in FIGURE 6 that the vanes *101* are each of substantially frusto-triangular form so as to conform substantially to the configuration of the housing of blower *80*. When the vanes *101* occupy substantially flat position as shown in FIGURE 5, they create greater pressure than they do when they are curved as shown in FIGURE 4, although motor *90* drives the impeller *85* at

a constant speed. This is due to the fact that the leading convex surfaces of the vanes 101 in FIGURE 4 do not provide an efficient air-trapping surface as impeller 85 rotates in a counterclockwise direction in FIGURE 4 and, thus, more eddy currents are created at the distal portions of vanes 101 so the air leaks past the vanes at the central and outer portions of impeller 85. It is apparent that the contour of the blades 101 is varied by loosening nut 100 on motor shaft 87, then circularly adjusting hub 97 and plate 96 relative to each other, after which the nut 100 is driven home, the disk being fastened against the shoulder at the juncture of the reduced portion of shaft 87 by nut 100.

The blower housing 80 is provided with an outlet opening 110 to which a clapper valve housing 111 is communicatively connected. Clapper valve housing 111 is provided with a balanced intake clapper valve 112 which is pivoted therein, as at 113, and normally closes outlet opening 110 of blower 80 under the influence of a balance weight 116 adjustably mounted on the stem of clapper valve 112. Clapper valve housing 112 has an access door 114 which is pivoted on housing 111 and held in closed position by a catch 115. The access door 114 is provided for adjusting the balancing weight 116 on the stem of clapper valve 112.

A conduit or pipe 120, connected to the outlet opening 110 of blower 80 by means of clapper valve housing 111, extends to a tubular coupling 121 for communication with an air intake opening 122 (FIGURE 8) provided in the front wall 21 of the main housing or enclosure 20. Opening 122 may be rectangular or circular, as desired. It will be noted that air inlet opening 122 in the front wall 21 of enclosure 20 communicates with the first or front compartment *a* of diffusion chamber 34.

Front wall 21 of housing 20 is also provided with an outlet opening 123 which communicates with the conditioning compartment *h* of diffusion chamber 34. It will be observed in FIGURES 9 and 10 that opening 123 communicates with a tubular coupling 124 to which one end of an outlet pipe 125 is connected. Outlet pipe 125 serves to connect outlet opening 123 to one or more gas-cock operated jet-type burners, not shown, of the well-known type, used in kitchen ranges, hot water heaters, refrigerators, Bunsen burners, and the like. Although opening 123 is shown to be square, it is apparent that it may be of circular or other shape, as desired. Coupling 124, at the outlet 123 of diffusion chamber 34, is provided with a balanced outlet clapper valve 126 pivotally suspended in tubular coupling 124 and which remains in a normally closed position by gravity.

Both intake clapper valve 112 and outlet clapper valve 126 are balanced so that the slightest flow of gas from outlet opening 123 through a burner or burners, not shown, will cause simultaneous opening of said valves. On the other hand, closing the gas cock of any such burners tends to permit the valves to return to closed position. Of course, when no gas is being used, the valve 126 may remain closed, the air within the diffusion chamber then remaining static or dormant under light pressure.

It should be noted that, regardless of whether the gas cock to a single burner or the gas cocks to a large number of burners are open, the pressure of the air within diffusion chamber 34 remains constant. This is also true when all gas cocks are closed, since the blades 101 of blower 80 will permit any excess volume of air above that required to maintain a desired pressure in chamber 34 to slip thereby.

Operation

Assuming that the apparatus is installed ready for use, a liquid hydrocarbon of the type having a boiling point above maximum ambient atmospheric temperature, such as commercial hexane, is introduced into the lower portion of diffusion chamber 34 to a level substantially as shown in FIGURE 9; that is, to a level below that of the lower ends of dry rovings 65a (below the level of the for-

5 aminated shelf 68), and above the ridges on the corrugated false bottom, which level is maintained by the controller 72 throughout the use of the apparatus, so that the lower ends of the primary absorbing members 65 are suspended in the liquid hydrocarbon.

10 As heretofore stated, it has been found that the lower ends of the primary absorbent members or primary bleached roving strands 65 should have at least one inch thereof immersed in the supply of liquid hydrocarbon, and the portions of these strands above the liquid hydrocarbon preferably should not exceed eight inches, since otherwise, the upper portions of the primary strands of roving 65 might become dry and might absorb some of the liquid picked up by the air from the lower portions thereof as the air moves thereby or the latter primary strands of roving might not then be sufficiently wet to transfer the desired amount of liquid hydrocarbon to the air moving thereby and/or therethrough.

15 When the correct supply of liquid hydrocarbon has been introduced into the diffusion chamber 34 of enclosure 20, the circuit to heating element 33 may be closed to thus heat the heating chamber 31 and the liquid hydrocarbon L to the desired temperature. Depending upon the particular type of liquid being used, it has been found 20 that best results are obtained, when using hydrocarbon having a volatility in the range of commercial hexane, by maintaining the temperature of the liquid hydrocarbon L at a moderate temperature of from 50° F. to 80° F. (at or below the vaporization point) while maintaining the 25 air in the heating chamber 31 at a corresponding temperature. At higher temperatures, the B.t.u. content of the resultant gas is too high, causing wastage of the gas at the combustion point. Of course, heating element 33 need not be energized when ambient temperature is 30 sufficiently high. Although ambient temperature may substantially exceed 80° F., the liquid L will not, as a rule, exceed 80° F.

35 Upon the liquid hydrocarbon contacting the lower ends of the primary strands of bleached roving 65 in diffusion 40 compartments *a-g* of chamber 34, capillary attraction causes the exposed portions thereof to become quite wet or very nearly saturated, depending upon the length of time the primary rovings 65 will have been partially immersed in the liquid hydrocarbon before the apparatus 45 was utilized. The electric motor 90 is energized to drive impeller 85 in blower 80. In the meantime, the impeller blades 101 have been so adjusted as to insure an output of from 1½ to 5 inches water gauge pressure, this pressure being maintained constant at all times in which 50 blower 80 is operating.

55 Clapper valve 112 (FIGURE 5) is also adjusted, by means of the balance weight 116, to maintain the same in closed position when the pressure on both sides of the same is between one-and-one-half and five inches water gauge pressure. Thus, upon initially starting the motor 90 of blower 80, clapper valve 126 (FIGURE 9) remains closed and clapper valve 112 (FIGURE 5) is opened until such time that impeller 85 has produced equal pressure on opposite sides of clapper valve 112. At this 60 point, clapper valve 112 closes and excess air picked up by impeller blades 101 slips past the blades, because of the blades 101 having been previously adjusted so that the output of the blower 80 cannot exceed the desired maximum of one-and-one-half to five inches water gauge pressure. It has been found most desirable to maintain a constant pressure of three inches of water (1.733 ounces per square inch), without variation, in enclosure 20.

65 As the air is circulated by blower 80, it is apparent that it is first drawn into the heating compartment 31 through the filtered opening 32, which filtered opening filters the air to remove small dust particles. Thus, the air passes through conduit 94, into blower 80 and then passes from the blower into diffusion chamber 34 of enclosure 20.

While the apparatus is dormant; i.e., while no gas is being used, blower 80 merely maintains the air in enclosure 20 under constant low pressure, but the air is then moving very little, if any. Thus, the air does not pick up any hydrocarbon from the primary strands of cotton roving 65. It is apparent, therefore, that the primary strands 65 absorb considerable amounts of hydrocarbon liquid from the supply and may even become saturated during dormancy of the apparatus. It should be noted that, even though each primary strand of bleached cotton roving 65 is shown looped over a corresponding rod 67, both lower ends of each such strand are immersed in the hydrocarbon liquid on the bottom of diffusion chamber 34.

Now, when the apparatus is initially utilized by opening the cock to a suitable jet or jets of a gas burner, not shown, connected to outlet pipe 125 following a substantial interval of dormancy, say four hours or more, the pressure produced by blower 80 causes air to move through the apparatus at very low velocity. During such movement of the air, blower 80 continues to maintain a pressure of one-and-one-half to five inches of water throughout each compartment *a-h* because of the partitions 45-51 and the openings 55-61 therethrough. Thus, the slowly moving air picks up or absorbs substantially uniform amounts of hydrocarbon liquid from all the relatively wet rovings 65 in all the diffusion compartments *a-g*.

However, since the wet rovings 65 will have absorbed considerably more hydrocarbon liquid during said interval of dormancy than they can absorb during continuous movement of the air thereby and may have even become saturated, it is apparent that the slowly moving air will pick up and have suspended therein an excess amount of hydrocarbon molecules above that which may burn efficiently in a given volume of air; i.e., the specific gravity of the gas thus formed will be too high.

As the gas is being consumed, however, the amount of hydrocarbon liquid, in the portions of the wet strands of roving 65 exposed above the liquid supply, gradually diminishes until the recovery rate or capillarity of the wet strands 65 is in equilibrium with the temperature and pressure of the slowly moving air.

The specific gravity of the gas also gradually reduces somewhat proportional to the rate at which the amount of hydrocarbon liquid diminishes in the wet strands of roving 65 so that, when absorption of hydrocarbon liquid from the wet strands 65 is in equilibrium with the recovery rate of the wet strands 65, the specific gravity of the gas will be within prescribed limits such as to burn with high efficiency.

From the foregoing description, it is apparent that the specific gravity of the gas formed in compartments *a-g* must be reduced before it reaches the burner or burners during that indeterminate interval in which the amount of liquid in the exposed portions of wet strands of roving 65 exceeds that which is necessary to produce gas of the correct specific gravity. Therefore, the gas flows from compartment *g* into conditioning compartment *h* where it passes through and past the dry strands of bleached cotton roving 65a disposed in the path of flow of said gas to the burner.

Due to the low pressure and velocity of the air passing through conditioning compartment *h*, the temperature of the air, the porosity of dry strands 65a, the mass of the dry strands 65a and, apparently, the capillary characteristic of dry strands of bleached cotton roving 65a and the volatility of the hydrocarbon, the dry strands 65a absorb or filter out from the gas only so much of the hydrocarbon molecules as exceeds those which must remain suspended in a given volume of the air in order to change the specific gravity of the gas to within such limits as to burn efficiently in the form of a clear, hot, blue flame.

For some reason which is not apparent to us, the loose dry strands of bleached cotton 65a continue to absorb only such excess molecules from the gas throughout the

operation of the apparatus, even though the specific gravity of the gas entering compartment *h* may be gradually reducing for some considerable time after the apparatus has been started; i.e., after the gas cock has been opened. It follows that, when the capillarity or recovery rate of the wet strands of bleached cotton roving 65 has reached equilibrium with respect to the rate at which liquid hydrocarbon is absorbed therefrom by the slowly moving air; at which time the specific gravity of the gas within compartment *g* is within prescribed limits of from 1.225 to 1.325 relative to air, the dry strands of roving no longer absorb any noticeable amount of hydrocarbon molecules from the gas, so the gas remains at the prescribed specific gravity from the time it leaves compartment *g* until it is consumed at the gas burner, even though the gas flows through compartment *h* in its course to the burner.

As with any type of gas producing apparatus, the size of the housing and the volume, velocity, pressure and temperature of the air flowing through the apparatus, as well as any turbulence effected in the air by various obstructions, are all highly critical elements to be considered in the manufacture of the present apparatus. Accordingly, the relative size of the openings 55-61 in the partitions 45-51 should be determined in the manufacture of the apparatus so as to insure that the air flows from the inlet opening 122 (FIGURE 8) through the successive compartments *a* through *h* of the diffusion chamber 34 at a constant predetermined pressure; that is, when the apparatus is not being used, the pressure of the air in each of the compartments *a-h* must be the same and, when one or more burners are being used, the pressure of air flowing through each compartment *a-h* must still be the same, particularly when it is considered that the air is moved through the apparatus under very low pressure. Thus, the size of the openings 55-61 relative to the corresponding partitions and chambers must be determined by suitable testing instruments during the course of manufacture of the apparatus.

It is apparent, therefore, that blower 80 constitutes an extremely important factor contributing to efficient operation of the apparatus, in view of the fact that it must deliver air at a critical pressure depending entirely upon the demands of the apparatus and the demands of the burners. The pressure in the diffusion chamber need not only be relatively low to insure that molecules of hydrocarbon are absorbed by the air and that the dry strands of bleached cotton roving will absorb any excess molecules of hydrocarbon to reduce the gas to the required specific gravity, but to further insure that the rate of flow of the air through the apparatus will not chill the air, thus enabling the air to absorb and diffuse the molecules of hydrocarbon from the primary absorbing means 65.

In actual practice, one embodiment of the improved apparatus had a diffusion chamber 34 which was approximately thirty-six inches long, eighteen inches wide and nine inches high from top wall 25 to the ridges of false bottom 30. The hydrocarbon liquid was two inches deep above said ridges and primary absorbing means 65, in the form of bleached cotton rovings were suspended approximately seven inches above the liquid level *L* with approximately one-and-one-half inches of the latter rovings being immersed in the hydrocarbon liquid. The secondary bleached cotton rovings 65a were suspended on the same level as rovings 65, but terminated approximately one inch above the liquid level *L*.

Each compartment *a-h* was approximately nine inches square in plan, thus having a usable volume above liquid lever *L* of approximately 567 cubic inches. Thus, the ratio of the volume of the primary or diffusion compartments *a-g* to the volume of the secondary or conditioning compartment was 7 to 1.

The ratio of the exposed portions of the wet rovings 65 to the dry rovings 65a by weight was approximately

40 to 1. There were approximately 300 yards of exposed .16 hank roving in compartments *a-g* and $7\frac{1}{2}$ yards of .16 hank roving in compartment *h*. Single-strand .16 hank bleached cotton rovings each having approximately $\frac{3}{4}$ of a turn per inch twist therein were used (134.4 yards per pound or 53 grains per yard). The sizes of the openings 56-58, 55 and 59-61 were approximately 4" x 4", 4" x $3\frac{3}{4}$ ", 4" x $3\frac{1}{2}$ ", 4" x $3\frac{1}{4}$ ", 4" x 3", 4" x $2\frac{3}{4}$ " and 4" x $2\frac{1}{2}$ ", respectively. The openings 122, 123 were two inches in diameter or one-and-three-quarters inches square.

In one experiment, commercial hexane was used as the liquid hydrocarbon. Pure hexane (C_6H_{14}) has a boiling point of 156.2° Fahrenheit, however, according to ATSM standards, commercial hexane has an initial boiling point of 151° F. and a dry point of 158° F. With an ambient temperature from 37° F. to 78° F. and the pressure in tank 20 held at three inches of water, the specific gravity of the gas flowing from the enclosure 20 was from 1.225 to 1.275 both when the apparatus was operated continuously for several hours and when the apparatus was initially operated following a relatively long period (four hours or more) of dormancy. The gas burns with an efficient, hot, blue flame when within the range of specific gravity mentioned above.

Other more highly volatile hydrocarbons such as pentane (C_5H_{12}) have been admixed with hexane with similar results. This may be desirable when the apparatus is used in relatively cold climates. However, the heating element 33 may be used for heating the air and the liquid hydrocarbon in enclosure 20 to the desired extent, below the boiling point of the hydrocarbon, if the hydrocarbon is not sufficiently volatile.

When the apparatus is used in warmer climates, heptane (C_7H_{16}) and octane (C_8H_{18}) may be used as the hydrocarbon liquid supply. Since heptane and octane have relatively high boiling points; i.e., 209.1° F. and 256.3 F., respectively, they are not entirely satisfactory in themselves and may be mixed with a more volatile hydrocarbon, such as hexane and pentane. It should be noted however, that the present apparatus is particularly adapted for converting hydrocarbon liquids to efficient gas, which liquids have a minimum boiling point above maximum outside atmospheric temperature or approximately 120° F. and a maximum boiling point of 160° F., and which gas must have a weight or density relative to air (specific gravity) of no less than 1.225 and no more than 1.325 in order to burn efficiently with a hot, blue flame.

In further actual practice, another embodiment of the apparatus had a diffusion chamber 34 and enclosure 20 similar to, and of the same size as, the previously described embodiment, but only two pairs of transverse partitions were used, such as partitions 46, 47, 50, 51, so that the diffusion chamber was divided into six equal sized compartments. Each of the compartments was approximately 9" x 12" in plan and nine inches deep with two inches of commercial hexane hydrocarbon liquid in the bottoms thereof. The partitions were provided with staggered openings, one in each partition, of progressively diminishing sizes varying from 4" x 4" to 2" x 4". The wet rovings and dry rovings were of the same size and arranged in substantially the same manner as in the previous embodiment, and their proportions were substantially the same as in the previous embodiment.

Although this arrangement provided each compartment with a usable volume of 754 cubic inches and the ratio of the volume of the diffusion compartments to the conditioning compartment was 5 to 1, the ratio of the exposed portions of the wet rovings to the dry rovings was still held at approximately 40 to 1 and the lengths of the rovings 65, 65a were also the same in both experiments, since the overall size of the diffusion chamber or enclosure was the same in both embodiments of the improved apparatus.

The gas produced during initial and extended operation of the second embodiment of the apparatus also had a specific gravity of from 1.225 to 1.275.

Experiments have shown that the present apparatus results in the production of a gas which considerably exceeds the heating capacity of the particular type of liquid from which the gas is converted. For example, a liquid having a rated capacity of one hundred thousand B.t.u.'s per gallon has been converted to a gas containing two hundred thousand B.t.u.'s per gallon of liquid.

10 It is thus seen that we have provided an improved apparatus for producing efficiently combustible gas, within given limits of specific gravity, from liquid hydrocarbons in which low pressure air is directed through relatively wet, highly absorbent, suspended strands or other highly absorbent material and then through and past dry bleached cotton rovings and wherein the porosity and capillarity of such rovings are such as to absorb from the gas only those molecules of hydrocarbon which may have been picked up by the air as it moved past the wet strands, 15 and which exceed the molecules which must remain in suspension in the air in order to result in a gas having a specific gravity within such limits as to burn with a hot, blue flame.

20

25 In the drawings and specification there have been set forth preferred embodiments of the invention and, although specific terms are employed, they are used in a generic and descriptive sense only and not for purposes of limitation, the scope of the invention being defined in the claims.

30 We claim:

1. A gas producing apparatus for use with gas-cock-operated jet-type burners comprising an enclosure for containing a supply of liquid hydrocarbon in the bottom portion thereof, said enclosure having a gas outlet above the level of said supply and adapted to be connected to a gas-cock-operated burner, highly absorbent capillary members suspended above and having their lower portions immersed in said liquid hydrocarbon, means maintaining air at a gauge pressure of .867 to 3 ounces per square inch in said enclosure whereby the air flows very slowly past and absorbs hydrocarbon molecules from said capillary members when the gas cock is opened, a plurality of bleached cotton rovings suspended between said capillary members and said outlet, said rovings being positioned in the path of the air flowing from said members to said outlet, said rovings being out of contact with said supply of liquid, and said rovings being approximately $\frac{1}{40}$ th the mass of said capillary members and having a capacity to remove molecules of hydrocarbon from the air only when the gas formed at said capillary members by the air and hydrocarbon molecules is above a predetermined range of specific gravity.

2. A gas producing apparatus for use with gas-cock-operated jet-type burners comprising an enclosure for containing a supply of liquid hydrocarbon on the bottom thereof, said enclosure having a gas outlet adapted to be connected to a gas-cock-operated burner, a first plurality of bleached cotton rovings suspended above and having their lower portions immersed in said liquid hydrocarbon, means maintaining air at a water gauge pressure of $1\frac{1}{2}$ to 5 inches in said enclosure whereby the air flows very slowly past and absorbs hydrocarbon molecules from said first rovings to form a combustible gas when the gas cock is opened, a second plurality of bleached cotton rovings suspended between said first rovings and said outlet, said second rovings being positioned in the path of the air flowing from said first rovings to said outlet, said second rovings being out of contact with said supply of liquid, and said second rovings being approximately $\frac{1}{40}$ th the mass of said first rovings and having a capacity to remove molecules of hydrocarbon from the gas only when the gas is above a predetermined range of specific gravity.

3. Apparatus according to claim 2 in which said first and second bleached cotton rovings are of approximately .16 hank and .75 twist per inch construction.

4. A gas producing apparatus for use with gas-cock-operated jet-type burners comprising an enclosure for containing a supply of liquid hydrocarbon in the bottom portion thereof, said enclosure having a gas outlet adapted to be connected to a gas-cock-operated burner, highly first absorbent, bleached cotton rovings suspended above and having their lower portions immersed in said liquid hydrocarbon, means maintaining air at a constant water gauge pressure of 1½ to 5 inches in said enclosure whereby the air flows very slowly past and absorbs hydrocarbon molecules from said first rovings when the gas cock is opened, said rovings being of such mass and capillarity as to normally retain an amount of liquid therein in equilibrium with the amount of liquid absorbed by the air flowing thereby to form gas within an efficient given range of specific gravity, second highly absorbent bleached cotton rovings suspended between said first rovings and said outlet, said second rovings being positioned in the path of air flowing from said first rovings to said outlet, said second rovings being out of contact with said supply of liquid, and the mass of said second rovings being approximately 1/40 of the mass of said first rovings and thus having a capacity to absorb molecules of hydrocarbon from the air only when the gas formed at said first rovings is above said efficient given range of specific gravity.

5. For use with a gas-cock-operated jet-type burner, a gas producing apparatus comprising an enclosure for containing a supply of liquid hydrocarbon on the bottom thereof, said enclosure having an outlet adapted to be connected to said gas-cock-operated burner, highly absorbent bleached cotton rovings suspended above and having their lower portions immersed in said supply of liquid, means introducing air into said enclosure and maintaining the air at a water gauge pressure of 1½ to 5 inches in said enclosure whereby opening of the gas cock permits air to flow very slowly past and absorb hydrocarbon molecules from said rovings to form a gas, a plurality of partitions in said enclosure defining a plurality of compartments through which the air must pass when flowing past said capillary members, each partition being provided with a relatively small opening through which said air passes, said partitions serving to retard flow of said air so as to induce uniformity of said air pressure throughout the compartments, capillary means consisting of loosely twisted, bleached cotton strands of a mass approximately 1/40 of the mass of said rovings for absorbing molecules of hydrocarbon from said gas only when the gas is above a given specific gravity, and means supporting said capillary means in the path of the gas flowing from said rovings to said outlet and out of contact with said supply of liquid.

6. A structure according to claim 5 having means for

heating the liquid hydrocarbon to a predetermined temperature.

7. A structure according to claim 5 including means for heating the air introduced into said inlet opening.

- 5 8. Apparatus for producing a gas from liquid hydrocarbon comprising an enclosure having a plurality of spaced partitions therein defining a series of compartments therein, said partitions being provided with relatively small openings therein establishing communication between adjacent compartments, said enclosure having an air inlet opening at one end of the series of compartments and an outlet opening at the other end of the series of compartments, means adapted for connecting said outlet opening to a gas-cock-operated burner, means for introducing and maintaining a supply of liquid hydrocarbon in a lower portion of said enclosure, a plurality of bleached cotton rovings suspended in each of said compartments, the lower ends of the rovings in the final compartment of said series terminating in spaced relation above the level of the liquid in the enclosure, the rovings in the compartments other than the final compartment having their lower portions, at least in part, immersed in said liquid, the rovings in said final compartment having a total mass in a ratio of approximately 1 to 40 relative to the total mass of the rovings in the other compartments, and an air impelling means connected to said air inlet opening and creating a constant air pressure of 1½ to 5 inches water gauge throughout the series of compartments and through the air outlet opening, said rovings in those compartments other than the final compartment being of such capillarity as to retain a greater amount of liquid absorbed from said supply while the gas cock is closed than they retain while the gas cock is open, opening of said gas cock causing air to flow from said impelling means through the enclosure whereby the air absorbs molecules of hydrocarbon from the rovings in those compartments other than the final compartment, and said rovings in the final compartment being such as to absorb from the air only such molecules of hydrocarbon necessary to maintain the gas thus formed at a specific gravity from 1.225 to 1.325.
